(57) **CLAIM**

The ornamental design for a light emitting diode barn light, as shown and described.

DESCRIPTION

FIG. 1 is a perspective view of a light emitting diode barn light, showing my new design;

FIG. 2 is another perspective view thereof;

FIG. 3 is a side view thereof;

FIG. 4 is a back plan view thereof;

FIG. 5 is a top plan view thereof; and,

FIG. 6 is a bottom plan view thereof.

The broken lines shown represent unclaimed subject matter and form no part of the claimed design.
